(57) **CLAIM**

The ornamental design for a headgear of a helmet, as shown and described.

DESCRIPTION

FIG. 1 is a perspective view of the design for the headgear of a helmet;

FIG. 2 is a top view of a design for the headgear of a helmet; FIG. 3 is a bottom view of a design for the headgear of a helmet;

FIG. 4 is a right hand view of a design for the headgear of a helmet;

FIG. 5 is a left hand view of a design for the headgear of a helmet;

FIG. 6 is a back view of a design for the headgear of a helmet; and,

FIG. 7 is a front view of a design for the headgear of a helmet.

In these drawings, the solid lines illustrate the claimed ornamental design, whereas the broken lines illustrate environmental features that form no part of the claimed ornamental design.
